UNITED STATES PATENT OFFICE.

JULIA HANNAH CROOK AND JOHN EDWARD CROOK, OF REMUERA, AUCKLAND, NEW ZEALAND.

WINDOW CONSTRUCTION.

1,396,359.

Specification of Letters Patent.

Patented Nov. 8, 1921.

Application filed August 23, 1917. Serial No. 187,764.

To all whom it may concern:

Be it known that we, JULIA HANNAH CROOK and JOHN EDWARD CROOK, subjects of His Majesty the King of the United Kingdom of Great Britain and Ireland, residents of Selwyn street, Remuera, in the city of Auckland, Provincial District of Auckland, and Dominion of New Zealand, married woman and builder, respectively, have invented a new and useful Improvement in Window Construction, of which the following is a specification.

This invention relates to windows, and its special object is to enable the outside surfaces of windows to be got at with ease and comfort and without risk to the workmen or other persons whose duties consist of cleaning, painting, reglazing or performing any other operation which requires to be done from the outside of the building, often several stories high, in which the window or windows are situated. Further, it also provides means in the case of sliding or liftable windows for the raising and lowering of the sashes, which can also be locked in any desired position.

Now, according to this invention, the sliding or liftable windows are constructed and hung so that they may be swung into the rooms or building while they are still also enabled to be raised and lowered in the usual way. This is enabled to be performed by hinging each sash at one side of the window (preferably the left hand), the hinges employed being of a special construction and having formed on their inner ends, runners adapted to be slid upward and downward in vertical guides recessed into the window stile. The stiles on both sides of the window are specially formed, so as to avoid the necessity of employing separate outer stops and parting slips, while the inner stops are hinged to open inward.

When weights are employed they are provided at the hinged side only of the window, and operate in the usual manner. The means for raising and lowering and locking the sashes when weights are not used do not in any way interfere with the hinging of the sashes. Said means consist of two screw rods recessed into the stile on the same side of the window as the hinges and extending the full length of the frame. In this case the hinges, of which there are

preferably two to each sash have formed at 55 their inner ends sockets or bosses screwed internally to work on the screwed rods, the hinges of the upper sash being mounted on the rear rod and the hinges of the lower sash on the front rod.

By means of a crank handle mounted through the inner facing, and toothed gearing between said crank handle spindle and the screwed rods, either of the latter can be revolved as required to force the hinges carrying the sash, upward or downward.

Casement windows are hung from the window frame by means of double knuckled hinges secured to the outside of the top and bottom bars of each sash. The sashes swing 70 outward in the ordinary way on the first or usual knuckles, and when it is desired to get at the outside of the window, same can be reversed on the second knuckles which are situated about midway of the top and 75 bottom bars, the hinges not being permanently fastened to the bars, between the knuckles.

The invention will be described in detail with reference to the accompanying drawings, in which,

Fig. 1 illustrates by means of an inside elevation a combination sliding and hinged window,

Fig. 2 is a sectional plan view taken 85 through Z—Z Fig. 1.

Fig. 3 is an enlarged sectional elevation through Y—Y, Fig. 1.

Fig. 4 is an enlarged sectional plan view of a window stile as used in Fig. 1 and Fig. 90 2 showing vertical guides fitted therein,

Fig. 5 is an enlarged perspective view of one of the vertical guides employed in Figs. 1, 2 and 4,

Fig. 6 is an enlarged perspective view of 95 the type of hinge used in Figs. 1 and 2,

Fig. 7 is an enlarged sectional plan of a recessed window stile showing guides fitted therein to suit,

Fig. 8 shows in enlarged perspective the 100 shape of guide used with a stile, as formed in Fig. 7,

Fig. 9 illustrates by means of an outside elevation a casement window hung by means of double knuckled hinges,

Fig. 10 is a plan view of the parts illustrated in Fig. 9,

Fig. 11 is a part elevation (shown broken)

of a combination hinged and sliding window fitted with raising and lowering means constructed according to this invention.

Fig. 12 is a face view of the window stile shown in Fig. 11, showing mounted on the rods the hinges which carry the sashes.

Fig. 13 is an enlarged sectional plan taken through X—X Fig. 11,

Fig. 14 is an enlarged detail view showing means for locking the main gear wheel, in mesh with either of the wheels operating the screwed rods, and

Fig. 15 is an enlarged detail view illustrating a means for preventing the screwed rods sagging.

Referring to the combination sliding and hinged window illustrated in Figs. 1, 2 and 11, the stiles 1 thereof are either stepped as illustrated in Fig. 4 or formed with inclined recesses 6^a as in Fig. 7. Both these formations of window stile obviate the use of separate outside stops and parting slips, the outside stops 2 being formed on the stile as a result of the plowing, while the stepping and recessing each dispense with the necessity for using parting slips.

With stiles formed as shown in Figs. 2 and 4 the upper sash 2^a slides between the opposite stops 3 against the outside stops 2, and the lower sash 3^a slides between the opposite stops 4, the inside stops 5 being hinged to the inside facing and closing against the lower sash.

In one of the stiles, preferably the left hand, are recessed vertical metal guides 6 one to each sash and running the full length of the stile 1 (see Fig. 4). These guides 6 are shaped as shown in Fig. 5 and are adapted to take the runners 7 of the hinges 8 of which there are preferably two to each sash, the hinges of the upper sash working in the rear guide 6 and the hinges of the lower sash in the front guide 6.

The sashes are weighted at one side only in the usual way, and when the inside stops 5 are opened to the position indicated by dotted lines in Fig. 2, they, the sashes, can be swung on their hinges 8 into the room or building as indicated (Fig. 2). The stops 5 when closed are secured against the stiles 1 by thumbscrews 8^a or other form of temporary fastening.

As will be seen from the foregoing owing to the formation of the hinges and the latter's engagement in the vertical guides 6, the sashes can quite readily and easily be moved up or down, and opened into the room or building at any position.

When the stiles 1 are formed with recesses 6^a as in Fig. 7, the vertical rails of the sashes are shaped to engage therein, the guides 6 being shaped to lie flush in the recesses while the runners 7 of the hinges are formed so as to work in the guides 6.

The means for raising and lowering the

sashes illustrated in Figs. 11 to 15 are situated at the same side of the window as the hinges 8. Two screwed rods 9 having top and bottom bearings 9^a are recessed into the stile 1, one opposite each sash. The hinges 8 in this case have formed at their inner ends internally screwed sockets or bosses 15 which engage and work on the rods 9, the hinges of the upper sash working on the rear rod 9 and the hinges of the lower sash 75 on the front rod 9. On each rod 9 is keyed a bevel pinion 10 and each pinion 10 has meshing therewith a bevel gear wheel 11 horizontally mounted. A crank handle spindle 12 mounted on the back of the stile 1 projects through the inside facing and carries a crank handle 13 at its outer end.

On the spindle 12 is keyed a gear wheel 14 with bevel teeth on both faces, the spindle 12 being mounted so that the wheel 14 may 85 be made to engage with either of the horizontal wheels 11. By pushing the spindle 12 carrying the wheel 14 inward the latter is caused to mesh with the wheel 11 engaging the pinion 10 on the rear rod 9, so that the 90 crank handle can then be revolved in either direction to cause the rear screwed rod 9 to be rotated as required to move the upper sash 2^a upward or downward.

On pulling the spindle 12 outward the 95 wheel 14 is caused to mesh with the wheel 11 engaging the pinion 10 on the front rod 9 and the latter can then be turned in the direction necessary to raise or lower the bottom sash 3^a.

To prevent the wheel 14 from coming out of toothed engagement with either of the wheels 11 when raising or lowering a sash a spring pawl 16 (Fig. 14) is pivoted in the inside facing about the spindle 12, with its 105 outer end projecting far enough to enable it to be pressed down in order that its rear end may be lifted out of either of the circular grooves 17, 18, in the spindle 12 when it is desired to change the engagement of the 110 wheel 14 with either of the wheels 11.

When the spindle is pushed in as far as it will go, or is in the position for operating the upper sash, the inner end of the pawl 16 rests in the first groove 17, and prevents any 115 end movement of the spindle, and when the latter is pulled out to its full extent or is in the position necessary for operating the lower sash, the second groove 18 is engaged by the inner end of the pawl 16.

Supporting bearings 19 to prevent sagging of the rods 9 occasioned by the weight of the sashes, are provided, these bearings 19 being fitted and secured in the recesses 20 in which the rods 9 are situated, to bear 120 against the bosses of the pinions 10.

In hanging casement windows, double knuckled hinges 21 are employed, the latter being somewhat like the ordinary T hinge, but with a knuckle 22 at each end. These 13

hinges (Fig. 9) are secured to the window frame 23 in the usual way, but the fastenings to the horizontal bars 24 of the sash are made about midway of the latter and beyond the second or outer knuckle 22.

To enable the window to be opened and shut as an ordinary casement window, a hole is made through the bottom bar at its inner end and a thumbscrew 25 inserted therein from the inside to engage in a screwed portion of the hinge. This locks the window to the hinges 21 so that the outer knuckles are not used, but when it is desired to get at the outside of the window, the thumb-screws 25 are disengaged from the hinge, whereupon the window can be swung or reversed on the outer knuckles 22 to occupy the position indicated by dotted lines in Fig. 10.

We claim:—

20 In combination, upper and lower window sashes; a frame wherein said sashes are mounted for vertical movement independent of each other; screw-threaded sash-control-

ling rods mounted in said frame, one for each sash and extending substantially the entire length of the frame, both of said rods being mounted at the same side of the sash; screw-threaded collars pivotally carried by each sash and engaging the respective sash-controlling rods each sash being capable of being swung on its pivotal connections with the collars; a beveled gear for each rod geared thereto; a shaft rotatably and slidably mounted in said frame; a manually operated crank on said shaft; and a double faced beveled gear mounted on said shaft and adapted to mesh with either of said beveled gears and to rotate the gear with which it meshes to move the sash associated therewith.
